United States Patent Office.

SHUBAEL E. HEWES, OF ALBANY, NEW YORK.

Design No. 4,885, dated May 9, 1871.

DESIGN FOR A HEATING-STOVE.

The Schedule referred to in these Letters Patent and making part of the same.

I, SHUBAEL E. HEWES, of the city and county of Albany and State of New York, have invented a new and improved Design for Heating-Stoves, of which the following is a specification.

Nature and Objects of the Invention.

My invention relates to a design for heating-stoves adapted for burning anthracite coal, and provided with a continuous jacket or casing extending from base to top, to inclose an air-heating chamber, substantially as described in an application which I have made of even date herewith, for the novel construction and internal arrangement of such stoves; but according to my present design the fuel-magazine is intended to be supplied at top instead of at the side, as described in my application before referred to.

Description of the Accompanying Drawing.

Figure 1 is a front view of a stove illustrating my invention.

Figure 2 is a top view of the same with the feed-door partly open.

General Description.

B represents the base of the stove.

E E¹ E² E³, the several parts of the external casing of the air-chamber.

O O' represent a cap made in two parts, one movable upon the other, to constitute a register for the discharge of heated air.

P represents the feed-door, and

K the exit-flue for the discharge of smoke.

The ash-pit door C and the illuminating fire-door D are both made to slide around and within the shell of the stove.

My design possesses novelty in the contour of the base B, in the conformation, and in the ornamentation of the curved rim E, in the converging of the section E² of the casing, in the ornamental configuration of the double cap O O', and in the ornamental configuration of the feed-door P and the top piece Q, which may or may not be made hollow to constitute an urn or vase for the reception of water.

I claim—

The design for heating-stoves, substantially as above set forth.

S. E. HEWES.
